UNITED STATES PATENT OFFICE.

FRANK H. DUNBAR, OF CLEVELAND, OHIO.

ASH GATE.

Application filed October 22, 1924. Serial No. 745,170.

This invention relates to closures for hoppers, and is particularly adapted to hoppers for receiving ashes or other loose material.

- 5 In the usual practice ash hoppers are designed to hold the hot ashes until they can be discharged in suitable transporting devices by opening the doors of a gate construction beneath the discharge opening.
- 10 In order to quench the hot ashes to prevent them from injuring the walls of the hopper and stoker or other parts of the furnace construction, considerable water is sprayed on them. It is desirable, therefore, to remove
- 15 this water in a satisfactory and efficient manner.

An object of my invention is to provide a door for such hoppers which will at all times receive and discharge easily and

20 quickly all such liquid without allowing it to escape and fall in undesirable places.

Another object of the invention is to provide a closure mechanism in which there is formed a seal to prevent leakage or overflow

25 of liquid around three sides thereof so that liquid from the hopper will be directed toward one end of the door and discharged therefrom.

These and other objects will be apparent

30 from the following description and attached

drawings forming a part of this application,

in which

Figure 1 is a plan view with part of the

frame broken away to show the flanges more

35 clearly.

Fig. 2 is a section on line 2—2, Fig. 1,

with parts omitted.

Fig. 3 is a section on line 3—3, Fig. 2,

with parts omitted.

40 The lower portion of one of the hoppers for holding ashes or other material is fragmentarily indicated in Fig. 2 and preferably consists of the usual metal supporting bars 1 lined with fire brick or other refractory

45 material 2. Surrounding the discharge opening of each hopper is a gate construction comprising a frame 3 having sides 4 and ends 5, and a door 6.

The sides 4 of the frame are preferably

50 of channel construction each having a vertical web 7 and flanges 8 and 9 projecting outwardly. The sides 4 are provided also with inwardly extending flanges 10 on which the refractory material may rest, the flanges

55 10 overlying the side portions of the door.

Depending from the flange 10 is a flange 11,

which latter preferably extends along the sides and ends of the frame 3.

The door 6 is carried by bracket arms 12 to which are attached rollers 13 to run on the track 14 formed by the flanges 9 of the frame. Suitable angle sections 15 may be secured to the sides of the gate frame to extend beyond the frame and thus form continuous tracks for the door rollers to engage when the door is moved beyond the frame.

Any suitable operating mechanism, such as a cylinder *c* actuating piston rod *c'*, may be utilized to open and close the door.

The door 6 comprises a body portion, the 70 surface of which is covered with refractory material 16, and upstanding flanges 17, 18 are carried by the door along the sides and projecting beyond the front. The rear of the door is provided with a flange 19 extending outwardly across the width of the door and having a drip edge. Thus water which is discharged through the hopper opening through the surface of the door will be directed by the side and front flanges 75 of the door toward the rear of the door and discharged therefrom.

In order to prevent leakage or overflow of water between the frame and side walls of the door, I have provided the side flanges 17, 80 85 18, disposed on both sides of the depending flanges 11 of the frame, there being a sufficient clearance between the flanges to permit easy operation of the door and prevent

binding between the door and frame. As 90 the inner sides of the flanges 18 are disposed lower than the depending flange 11 of the frame, the ashes or other loose material in the hopper will gradually accumulate in the channel formed between the flanges 17 18 95

and above the connecting web 17^a of the door. The flange 11 is preferably made with a notched bottom portion comprising projecting lugs 20, the edges 21 of which act as plows and cause any excess material 100 to be gathered in the notches 22 upon opening the door. When the door is open the ash drops from the notches 22 of the bar and thus the flange becomes a self-cleaning

105 scraper to keep the ash or loose material from packing hard enough to cause binding between the door and frame. The flange 11 at the front of the frame is interrupted, as at 11^a, to permit the door flange 18 to move forward and backward.

110 At the front of the door the outwardly and upwardly inclined flange 24 projects in

front of the depending flange 11 on the frame. Preferably a packing member 25 of flexible material is secured to the frame so that it will extend downwardly from the frame to be engaged by the upper edge of the flange 24 when the door is in closed position to keep the liquid from leaking out over the top of the flange 24.

Preferably a collecting trough 26 is carried by the frame and disposed so that it will receive the liquid discharged from the surface of the door at the rear of the door. The trough 26 extends across the rear of the door and is of any convenient cross sectional shape. By means of outlet 27 or the like the liquid in the trough may be conducted from the trough and directed into any desired channel.

A suitable flange 28 depends from the frame and directs water escaping under pressure between the surface of the door and the depending flange 11 into the trough 26.

It will be seen that provision is made for keeping the surface of the door between the flanges 17 and 18 automatically clean, so that binding between the door and frame will not occur.

Furthermore, it is to be understood that the particular forms of apparatus shown and described, and the particular procedure set forth, are presented for purposes of explanation and illustration only and not by way of limitation and that various modifications of said apparatus and procedure can be made without departing from my invention as defined in the appended claims.

What I claim is:

1. A hopper provided with a bottom discharge opening, a frame surrounding said opening, a door associated with said frame and slideable to open or close the opening, depending flanges at the sides of the frame and upwardly extending flanges carried by the door at each side thereof to form a channel for said depending flange of the frame.
2. A hopper having a discharge opening,

a frame surrounding said opening and a door movable to close and open said opening, two upwardly extending flanges on each side of said door, and a downwardly extending flange on each side of said frame extending between said door flanges, and means for removing ashes from between said door flanges when the door is moved.

3. A hopper having a bottom discharge opening, a frame surrounding said opening, a depending flange along each side of said frame, a door for closing said opening and movable relative to the frame, two upwardly extending flanges at each side of said door forming a trough into which the flange of the frame extends, and means carried by the frame flanges for scraping ashes in such trough when the door is moved.

4. A hopper having a bottom discharge opening, a frame surrounding said opening and having a depending flange along each side, a door below said frame and movable relatively thereto to open and close said opening, a trough along each side edge of said door and adapted to receive a downwardly depending flange of the frame, said flanges being provided with serrated edges to scrape ashes from said troughs.

5. A hopper having a bottom discharge opening, a frame surrounding said opening, a depending flange along each side edge of said frame, a door associated with said frame to open or close said opening, a trough carried by each side edge of the said door and extending above the top surface of said door to embrace said frame flange, and a notched edge on each of said flanges for scraping ashes from said troughs.

6. A hopper having a discharge opening, a frame surrounding the opening, a door movable to open and close the opening and provided with a trough along each side, and two serrated flanges depending from the frame into said troughs.

In testimony whereof, I hereunto affix my signature.

FRANK H. DUNBAR.
